FIG. 2 is a front view of the design shown in FIG. 1;

FIG. 3 is a right side view of the design shown in FIG. 1;

FIG. 4 is a back view of the design shown in FIG. 1;

FIG. 5 is a left side view of the design shown in FIG. 1;

FIG. 6 is a top view of the design shown in FIG. 1; and

FIG. 7 is a bottom view of the design shown in FIG. 1.

FIG. 8 is a perspective front view of another embodiment of an absorbent article package embodying the new design;

FIG. 9 is a front view of the design shown in FIG. 8;

FIG. 10 is a right side view of the design shown in FIG. 8;

FIG. 11 is a back view of the design shown in FIG. 8;

FIG. 12 is a left side view of the design shown in FIG. 8;

FIG. 13 is a top view of the design shown in FIG. 8; and

FIG. 14 is a bottom view of the design shown in FIG. 8.

FIG. 15 is a perspective front view of another embodiment of an absorbent article package embodying the new design;

FIG. 16 is a front view of the design shown in FIG. 15;

FIG. 17 is a right side view of the design shown in FIG. 15;

FIG. 18 is a back view of the design shown in FIG. 15;

FIG. 19 is a left side view of the design shown in FIG. 15;

FIG. 20 is a top view of the design shown in FIG. 15; and,

FIG. 21 is a bottom view of the design shown in FIG. 15.

Solid lines shown in the figures described above form the claimed design. Broken lines shown in the figures described above are for illustrative purposes only and form no part of the claimed design.
